INVENTOR

BY Victor J. Evans

ATTORNEY:

UNITED STATES PATENT OFFICE.

JAMES R. TAYLOR, OF SPEARMAN, TEXAS.

PROPELLER.

Application filed September 19, 1927. Serial No. 220,568.

The present invention relates to propellers and particularly to propellers adapted for use on aeroplanes and motor boats.

Objects of the invention are to provide for the adjustment of the propellers so as to vary the draught thereof and to place the control of this adjustment under the control of the operator of the machine.

Further objects are to provide for the increase and decrease of propulsion power without changing of motive speed or power, and to provide for the reversal of the driving force under control of the operator, and to provide for the braking action incident to the operation of the propeller.

Still further objects are simplicity of construction, cheapness of manufacture, durability and effectiveness in use, and simplicity of operation.

20 In the drawings:

Figure 1 is a rear elevation of the propeller.

Figure 2 is a side elevation showing the same attached to the rear of an aeroplane.

25 Figure 3 is a section on the line 3—3 of Figure 2 showing the relation of the sliding block to its housing and to the sliding collar.

Figure 4 is a section on the line 4—4 of Figure 3, looking in the direction of the arrows and showing the relation of the adjustment disks to the sliding block and to the shafts of the propeller blades.

Figure 5 is a perspective of the two adjustment disks.

Referring to the drawings in detail, 10 designates the rear end of the body of an aeroplane, from which the propeller shaft 11 projects. The propeller shaft has mounted thereon at its rear end the housing 12 having a chamber 13 formed therein to receive the 15 sliding block 14 movable rearwardly and forwardly relative thereto. Rigidly connected with said sliding block by means of machine screws 15 is a sliding collar 16 having an annular groove 17 on the periphery thereof, said collar being held against longitudinal movement relative to the machine screws by shoulders 18 and the heads 19 of the machine screws between which the sliding collar is held. The 20 sliding collar is mounted against torque on a rectangular slideway 20 formed on the shaft 11 and constituting a part of the housing 12.

21 designates the propeller blades which are secured at their inner ends to shafts 22. The inner ends 24 and 24^a of said shafts are 25 projected into an elongated slot 25 formed in the sliding block and extending parallel with

the longitudinal axis of the aeroplane or boat. The end 24 is cupped to receive therein the other end 24^a, both of the ends being surrounded by a collar 24^b, the cupped end 24 60 forming a bearing for the end 24^a. Secured upon the shafts 22 and resting between the sliding blocks and the side walls of the housing are adjustment disks 26 having pins 27 extending from the adjacent faces thereof between the center and the periphery of the disks, said pins being projected into slots 28 formed in the sliding block and extending at right angles to the slot 25.

The rear end of the housing is preferably 70 closed by a cap 29 removably secured to the rear face thereof to provide for access to the moving parts for purposes of repair or inspection. The cap is preferably held in place by means of screws 30 and the housing is preferably formed of two parts 12^a and 12^b held together by means of screws 31, the bearing chamber 13 being partially formed in both of the sections, whereby it will appear that the propeller blades with their shafts may be 80 readily removed from the housing without disassembling the blades from their shafts and from the adjustment disks. Collars 40 are formed on the housing continuous with the bearings and a part of each collar being 85 formed on each section 12^a and 12^b.

The slideable collar 16 is operable from the driver's seat by means of a bell crank lever 32 pivoted to the bracket 33 mounted on the rear of the aeroplane body and having a 90 yoke 34 on one arm thereof, said yoke having pins 35 projecting into and riding in the groove 17 of the sliding block, the other arm 36 of the bell crank lever being connected to the link 37 of a suitable operating lever 95 (not shown) and in the reach of the driver of the machine.

It is believed that the operation of the device will be apparent from the above description which, however, is briefly as follows: when it is desired to turn the propeller blades to any given angle, it is only necessary for the operator to move his hand lever to such a position as will move the sliding block along its slideway, turning 105 the blades 20 through the instrumentality of the sliding collar, sliding block connections and the rotation of the adjustment disks to such position as will bring the blades into a proper angle to the housing. By this means 110 the blades may be adjusted to any angle and any draught of air or water may be obtained

as will be found desirable or necessary to accomplish the desired result, and the blades may be completely reversed, thus operating as a brake to slow down or stop the machine 5 within a comparatively short distance. The device places the control of the speed and driving power of the propellers under the control of the operator and makes it possible for him to adjust the blades so as to make 10 any degree of variation he may desire. By this arrangement not only may the speed and driving power of the machine be varied, but a saving in fuel may be accomplished, and the adjustment may be made without varying 15 the speed or power of the engine. The above advantages have been accomplished in a simple and economical manner and one which will commend itself to operators in the simplicity of operation and the durability of the 20 mechanism.

Having described my invention, what I claim is:

1. A propeller comprising a housing having rotatable blades extending radially therefrom, said blades being provided with shafts 25

journaled in the walls of said housing, disks on said shafts and rotatably mounted in said housing, a sliding block in said housing having radial slots and an axial slot therein, pins on said disks projecting into said radial slots, 30 said axial slot receiving the adjacent ends of the shafts, and means for sliding said block in said housing for varying the blade angle.

2. A propeller comprising a sectional housing having a chamber therein, a block slidably mounted in said chamber, blades, shafts having one of their ends secured to said blades, disks secured to the opposite ends of said shafts and arranged in said chamber, a cupped inner end for one of said shafts 40 and receiving the inner end of the other shaft for interfitting relation therewith, said block having an axially arranged slot therein to receive said inner ends, pins extending from the disks and received in radially arranged 45 slots in the block, and manually operated means for moving the block to vary the angles of the blades.

In testimony whereof I affix my signature.
JAMES R. TAYLOR.
